J. G. STADELMAN.

WOODEN BUILDING.

APPLICATION FILED JULY 17, 1919.

1,423,468.

Patented July 18, 1922.

Fig. 2

A technical line drawing of a structural component, possibly a bracket or a support. The drawing shows a main body with a vertical flange on the right. Several parts are labeled with numbers: 51, 52, 53, 54, 55, 46, 49, 36, 48, and 47. Part 51 is a diagonal rib, 52 and 53 are top flanges, 54 is a side flange, 55 is a bottom flange, 46 is a vertical rib, 49 is a horizontal rib, 36 is a slot or opening, 48 is a rib on the bottom flange, and 47 is a rib on the bottom flange. The drawing uses cross-hatching to indicate different materials or sections.

Fig. I

This technical drawing illustrates a concrete structure, likely a foundation or wall, with various components labeled with numbers. The structure is shown in perspective, with a vertical concrete column on the left and a larger rectangular base on the right. The base is labeled with numbers 11, 12, 13, 14, 15, 16, 17, 18, 19, 20, 21, 22, 23, 24, 25, and 26. A vertical column on the left is labeled with numbers 11, 12, 13, 14, 15, 16, 17, 18, 19, 20, 21, 22, 23, 24, and 25. A label 'B' is positioned above the top right corner of the base structure. A label 'a' is located on the left side of the vertical column. The drawing uses cross-hatching to indicate different materials or layers within the concrete structure.

Atlys.

UNITED STATES PATENT OFFICE.

JOSEPH G. STADELMAN, OF CHICAGO, ILLINOIS.

WOODEN BUILDING.

1,423,468.

Specification of Letters Patent. Patented July 18, 1922.

Application filed July 17, 1919. Serial No. 311,576.

To all whom it may concern:

Be it known that I, JOSEPH G. STADELMAN, a citizen of the United States, and a resident of Chicago, in the county of Cook, 5 State of Illinois, have invented certain new and useful Improvements in Wooden Buildings, of which the following is a specification.

My invention relates to portable sectional 10 buildings, particularly smaller wooden buildings such as residences, garages, etc. The invention in this case concerns particularly improved sill and corner post construction and arrangement which greatly facilitates 15 assembly of the structures and also makes them more rigid and weather proof.

From the following specification and the accompanying drawings, my invention will be clearly understood. On the drawings— 20 Fig. 1 is a vertical sectional view of one side of a house,

Fig. 2 is an enlarged horizontal sectional view to show in detail the construction and arrangement of the corner posts in connection with the side sections of the house, 25

Fig. 3 is a perspective view of a corner showing the sill construction,

Fig. 4 is a perspective view of a corner post which co-operates with the sill, and

Fig. 5 is a plan view of a corner with the post in section showing the manner of securing the post to the sill.

The sill structure is mounted on suitable foundations such as concrete posts 10. The 35 sill frame is composed of longitudinally and transversely extending side members A and B which are fitted together at their corners to form supports for the corner posts, the transverse members being also adapted to receive the floor joists. The sill members 40 may be formed out of solid timbers but are preferably built up. As shown, each of the sill members A comprises an inner board 11, an outer beam or board 12 and a spacer 45 or filler board 13. The inner and outer boards are of the same height but the filler board 13 is not so high in order to provide a longitudinally extending groove 14 in the top of the sill member. The outer board 12 50 is cut away at its upper outer corner so as to provide the supporting shoulder or ledge 15, the corner of the ledge being cut away to provide a water-shed surface 16. Between the shoulder 15 and the groove 14 is the

tongue 17. Below the shoulder 15, the outer 55 board 12 has the longitudinally extending groove 18, the section 18' between the groove and the shoulder 15 forming a drip cap.

The lower side of the groove 18 is tapered 60 to form the water-shedding surface 19, this surface together with the drip cap and the shedding surface 16 tending to keep water from soaking into the wood, the tendency for the water being to drop or run off the board as rapidly as possible. 65

Each of the sill sections B comprises an outer board 12 and a filler board 13 similar to those of the sections A. The inner side of the sections B may be a single board provided with vertical joist receiving slots 20, 70 or a lower joist supporting strip 21 may be provided and board lengths 22 above the strip and spaced apart to leave the joist receiving slots 20. It is to be understood that the various boards and other parts 75 which build up the sill sections are rigidly nailed, bolted or otherwise secured together. The sill sections are laid on the foundation posts and at their corners may be secured together by angle plates 23'. The inner 80 boards of the sections abut as clearly shown in Fig. 3, the inner boards of the sections B abutting against the adjacent side of the inner boards of the sections A. The outer ends of the outer boards 12 extend into 85 abutting engagement and at their inner sides these boards are cut away to leave vertical notches 23 and 24. The inner edge of the section A at each corner is cut away to leave the notch 25 as clearly shown in Figs. 90 3 and 5. The notches form rectangular sockets for corner posts 26. In Fig. 4, one of these corner posts is shown. Each post has at its lower end the bolt holes 27 and 28 for receiving bolts 29 and 30 for rigidly 95 securing the post to the outer boards of the adjacent sill sections. After the sill members have been laid on the foundation and secured together, the corner posts are applied in their sockets and secured to the 100 outer boards of the sill members by the bolts 29 and 30, the structure being then ready to receive the building side sections and the roof part.

After the sill structure has been mounted 105 on the foundation, the joists 31 are applied. These joists engage at their ends in the vertical notches 20 of the sill sections B and

the lower corners of the joists may be cut away to receive the supporting strip 21. The foundation wall 10 is wider than the sill members in order that the joists may 5 find resting surface on said foundation as clearly shown in Fig. 1.

The outside walls of the house consist of sections C comprising side studding members 32 and 33, cross braces 34 and siding 10 boards 35. At their lower ends the side studs at each section are notched at their inner corners to receive a board or beam 35' which extends horizontally a distance 15 downwardly beyond the lower ends of the studs. The upper ends of the studs of each section are connected together by a top cross brace 36. At its lower end the siding 35 extends a distance beyond the lower ends of the side studs. The side sections are 20 applied at one end of a sill member, the corner posts at two of the diagonally opposite corners being preferably temporarily left off the sill structure. The side sections are applied by engaging their side studs with 25 the tongues 17 of the sill members and with the boards 35' engaging in the groove 14, the lower ends of the siding boards engaging along the outside of the tongue 17 on the ledge 15.

30 When thus applied the side sections may readily be slid along the sill member and against the post at the opposite end. The side studs of the wall sections are provided with bolt holes 37 and the corner posts are 35 provided with bolt holes to register therewith. In order that all the wall sections may be interchangeably used, the post holes are uniformly applied, and the bolt passageways 38 and 39 through the post are therefore in the same plane. Preferably each 40 post is counter-sunk at the desired place as indicated at 40 for the reception of a bolt 41, the countersink being deep enough so that a bolt 42 may extend at right angles 45 through the post and passageway 39 and at the center of the post. This arrangement is clearly shown in Fig. 2 and enables the wall sections to be interchangeably used.

As shown the wall section of one wall 50 has been slid along the corresponding sill member and against one of the corner posts 26, the bolt 41 being applied through the post passageway 38 and through the registering bolt hole 37 of the wall section. The 55 adjacent wall section of the other wall is shown about to be received by the bolt 42. After the nuts are applied to the inner ends of the bolts and drawn up tight, the adjacent wall sections are securely anchored 60 to the post. The various wall sections for forming the complete side walls of the building are then applied to the sill beams and bolted one to the other by bolts 43 passing through the adjacent side studs of the sections. As the wall sections are securely

70 bolted together and to the corner posts and the corner posts are firmly socketed and bolted in the sill structure, the wall structure is very rigid and securely anchored to the sill frame.

75 The engagement of the sill member tongue 17 in the grooves of the wall sections, between the boards 35 and extended ends of the sill boards, assist in holding the walls aligned, and this tongue and groove engagement also effectively seals against the weather. The wall siding boards extending downwardly to the ledges 15 on the sill members, water will flow from the walls and along the shed surfaces 16 of the drip head 80 18'. The engagement of the wall section boards 35' in the sill groove 14 also adds to the stability of the side sections and with all this tongue and groove engagement and the shed surfaces and drip head construction, it is impossible for moisture to creep 85 in or for air to circulate between the lower ends of the wall sections and the sill frame. The built up side walls of the building extend from post to post and corner angles 90 comprising boards 44 and 45 are provided for each corner to complete the siding construction. The siding boards are preferably 95 of the tongue and groove type so that their connection one with the other is weather proof.

100 After raising of the building side walls, the roof structure is applied. As shown in Fig. 1, wall plate structures E are applied to the tops of the side walls and are connected together at their ends. Each wall plate may be formed integral of timber or built up of boards 46, 47 and 48 properly secured together and off-set to provide a notch 49 for receiving the upper ends of 105 the wall section siding boards. The inner boards 46 of the wall plates rest on top of the side section studs. The roof supporting rafter structures 50 are supported on the wall plates and the upper cross beams 36 of the wall side sections, the rafter boards 51 being notched with the wall plates in a manner well understood. Cross boards 52 extending between the rafter boards are notched at 53 to receive the upper edges of 110 the outer boards 48 of the wall plates. After the rafter structures have been applied, the roof boards 54 are secured thereto and suitable shingles or other roofing material 115 applied.

120 The floor 56 in the form of sections is now laid on the joists 31 and finish moulding 57 applied in the corners. The wall plates are bolted to the upper ends of the corner posts and also to the studs of the side wall sections, so that the sill, wall and roof parts are firmly and rigidly connected together.

I claim:—

1. In portable house construction, the combination of a sill beam, and side wall 130

sections, a longitudinally extending groove in the top of said beam, the upper outer corner of said beam being cut away to leave a supporting ledge, each side section comprising vertical studs, a board secured to the inner lower ends of said studs, and siding boards secured against the outside of said studs, said board secured to the inner lower ends of said studs and siding boards engaging in said groove and on said ledge respectively, and said studs engaging on said beam between said groove and ledge.

2. In a portable house, the combination of sill beams secured together at their ends, each beam having a longitudinally extending groove in its upper side, the junctions of said grooves at the beam ends being enlarged to form sockets, vertical corner posts supported in said sockets, and side wall sections, each section having a downwardly extending tongue for engaging in the sill beam groove, siding boards for each section extending downwardly a distance along the outsides of said beams, said wall sections being secured to each other and the end wall sections being secured to said corner posts.

3. In portable building construction, the combination of a sill frame comprising longitudinal and transverse sill beams joined at their ends, each beam having a longitudinally extending groove in its upper side and said grooves meeting at the beam ends, the junctions of said grooves being enlarged to form sockets, corner posts supported in said sockets, and side wall sections, each section comprising vertical studs resting on said sill beams, inner boards extending from said studs and forming tongues for engaging in the sill beam grooves, and siding boards secured to the out sides of said studs for overhanging the outside of said sill beams, the studs of the end sections being secured to said corner posts.

4. In portable house construction, the combination of a sill frame comprising sill beams joined at their ends, said beams having longitudinally extending slots in their upper sides meeting at the frame ends, the junctions of said grooves being enlarged to form sockets, and corner posts engaging in said sockets,

and bolts securing said posts to the outer walls of said sockets.

5. In portable house construction, the combination of sill beams joined at their ends, each beam comprising an inner and an outer 55 and an intermediate board all secured together, said intermediate board being of less height than the other boards in order to leave a longitudinally extending groove in the top of each beam, the grooves of the 60 joined beams meeting and being there enlarged to form sockets, vertical posts received in said sockets, the outer boards at the ends of the beams having bolt holes and said posts having bolt holes for registering with 65 said sill board bolt holes.

6. In portable house construction, the combination of sill beams, corner posts supported on said beams, and side wall sections comprising supporting studs and connecting 70 boards, said studs having bolt holes and said corner posts having longitudinally and transversely extending bolt holes for registering with the stud bolt holes, one of the bolt holes of each set in the post being countersunk to permit application of bolts in the same plane, one of the bolts being disposed in front of the other bolt, and thereby making the side wall sections interchangeable.

7. In portable house construction, the combination of a sill frame comprising sill beams joined at their ends, said beams having longitudinally extending grooves in their upper sides meeting at the frame ends, the junctions of said grooves being enlarged to form 85 sockets, corner posts engaging in said sockets, side wall sections, the upper outer corners of said sill beams being cut away to leave supporting ledges, each side wall section comprising vertical studs, a board secured to the inner lower ends of said studs, and siding boards secured against the outside of said studs, said board secured to the inner lower ends of said studs and siding boards engaging in said groove and on said 90 ledge, respectively, and said studs engaging on said beam between said groove and ledge.

In witness whereof, I hereunto subscribe my name this 9th day of July A. D., 1919.

JOSEPH G. STADELMAN.
